(57) **CLAIM**

The ornamental design for the side and top panels for a desktop computer case, as shown and described.

DESCRIPTION

FIG. 1 is a perspective view of the side and top panels for a desktop computer case, showing the top and right side panels installed on a desktop computer. The front panel of the computer case shown in broken lines is for illustrative purposes and forms no part of the claimed design.

FIG. 2 is a top plan view of the side and top panels for a desktop computer case.

FIG. 3 is a left side view of the side and top panels for a desktop computer case. The right side view is a mirror image of the left side view; and,

FIG. 4 is a cross-sectional view of a portion of the side and top panels for a desk top computer case taken along 4—4 FIG. 1 and showing through the holes.
